UNITED STATES PATENT OFFICE.

DOUGLAS C. KELLOGG, OF JACKSON, MICHIGAN, ASSIGNOR TO KELLOGG CORSET COMPANY, OF JACKSON, MICHIGAN.

ABDOMINAL SUPPORT.

Application filed June 8, 1925. Serial No. 35,828.

This invention relates to improvements in abdominal supports.

The main object of this invention is to provide an improved abdominal support which is very effective as a support and may be adjusted to the form and meet the conditions of the wearer.

Objects relating to details and economies of construction and operation will definitely appear from the detailed description to follow.

I accomplish the objects of my invention by the devices and means described in the following specification. The invention is clearly defined and pointed out in the claim.

A structure which is a preferred embodiment of my invention is clearly illustrated in the accompanying drawing, forming a part of this invention, in which:

Fig. I is a front perspective view of my improved abdominal belt or support, portions of a figure being shown to illustrate the position upon the body.

Fig. II is a fragmentary elevation showing one of the hip sections extended.

Fig. III is a fragmentary view showing the details of the connections for the front section to one of the hip or side sections.

Fig. IV is a detail section on a line corresponding to line 4—4 of Fig. III.

Fig. V is a fragmentary rear view showing the adjustable lacing connections for the hip sections.

In the drawing similar reference characters refer to similar parts throughout the several views.

Referring to the drawing, my improved belt or support comprises a front section 1 of non-elastic material having pockets 2 therein in which metal plates 3 are disposed. These metal plates are of bendable or conformable metal, preferably aluminum or other light weight material and are disposed in an upwardly and outwardly inclined relation relative to the center of the front section, the plates being preferably tapered upwardly as illustrated. The plates are disposed in an outwardly diverging relation so that they lie over the Poupart's

ligaments and are bent to conform to the figure and the requirements of the wearer. The front section is without stiffening material other than these plates.

The hip sections 4 and 5 are substantially duplicates, the hip section 4, however, being permanently secured at 6 to one side edge of the front section while the hip section 5 is detachably connected to the opposite edge, as by means of the snap fasteners 7 and the hooks and eyes 8 and 9. The rear edges of the hip sections are adjustably connected by laces 10, there being a plurality of laces rove through the eyelets 11, the ends of the laces being connected to tabs 12 so that stress is simultaneously placed on all of them. These tabs have buckles 13.

The adjusting straps 14 are secured to the front section, the one strap being permanently connected to the front section at 15 and the other detachably connected by means of the hook and eye 9, the end of the strap being stitched to the front edge of the hip section so that the hook and eye members can be disengaged when it is desired to remove the belt.

My improved belt or support is highly efficient, is readily adapted to the needs of the particular wearer and, if desired, pads can be attached to the inside of the front section which is double walled, the pads being suitably positioned and of suitable character for a wearer suffering from hernia, floating kidneys and the like.

The hip sections are provided with spaced stiffeners indicated at 16 to prevent wrinkling thereof.

Having thus described my invention, what I claim as new and desire to secure by Letters Patent, is:

An abdominal belt comprising a front section having upwardly tapered bendable metal plates set therein in an outwardly inclined relation to lie over the Poupart's ligaments, said plates being adapted to retain the form into which they are bent under such stresses as they are commonly subjected to on the wearer, the front section being otherwise without stiffening material,

hip sections connected to the side edges of said front section, the connection for one hip section to the front section being detachable, an adjustable lacing connection for the rear edges of said hip sections comprising a plurality of crossed laces, the ends of the laces being connected to tabs provided with

buckles, and adjusting straps coacting with said buckles and secured to the front section in opposed relation adjacent the lower 10 edge thereof.

In witness whereof I have hereunto set my hand.

DOUGLAS C. KELLOGG.
